(57) **CLAIM**

The ornamental design for a shaft instrument for shaving tissue, as shown and described.

DESCRIPTION

FIG. 1 is a front, left side isometric view of a shaft instrument for shaving tissue in accordance with the new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front side elevational view thereof; and,

FIG. 7 is a rear side elevational view thereof.

FIGS. 1-5 show a break indicating two parts of the shaft instrument for shaving tissue for ease of illustration. The additional broken lines shown in FIGS. 1 and 6 illustrate portions of the shaft instrument of shaving tissue that form no part of the claimed design.

1 Claim, 6 Drawing Sheets
